UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

CRUSHING-MACHINE.

SPECIFICATION forming part of Letters Patent No. 691,593, dated January 21, 1902.

Application filed May 5, 1899. Serial No. 715,714. (No model.)

To all whom it may concern:

Be it known that I, MORTON G. BUNNELL, a citizen of the United States, residing at Chicago, in the county of Cook, State of Illinois, 5 have invented a certain new and useful Improvement in Crushing-Machines, of which the following is a specification.

My invention relates more particularly to a construction of crushing-machine in which a 10 movable crushing-jaw is supported by a pair of swinging links or hangers and in which the jaw thus adapted to coöperate with a stationary jaw is operated by a suitably-actuated pitman.

15 Objects of my invention are to secure a better and more advantageous distribution of the strain; to reduce the strain upon the cast-iron portions of the machine to a minimum; to facilitate the adjusting of the machine with 20 respect to the character of the material to be crushed and also for the purpose of changing or varying the size of the product; to provide a light, simple, compact, and highly-efficient crushing-machine and one capable of developing 25 a maximum of crushing-power, and to provide certain details and features of construction tending to increase the serviceability and general efficiency of machines of this class.

30 To the attainment of the foregoing and other useful ends the pitman and movable jaw may be connected by an arm projecting from the back of the jaw, and the lower end of the pitman can be actuated by an eccentric, while 35 its upper end is preferably connected with the forward portion of the crusher-frame by means of a couple of swinging tension-rods. The movable crushing-jaw can be supported by a couple of swinging links or hangers, having 40 their lower ends pivotally connected with the lower portion of said jaw and their upper ends pivoted to the crusher-frame, and with this arrangement the jaw will have a combined vibratory and bodily forward-and-back movement and also a certain extent of 45 up-and-down movement. Preferably the connection of the tension-rods with the crusher-frame is such that the rods swing about an axis located forward of the stationary jaw, 50 and the connection is also such that the rods may be adjusted longitudinally for the pur-

pose of adjusting the movable jaw toward or away from the stationary jaw and thereby changing or varying the size of the product at will. The location of the axis about which 55 the tension-rods swing may be such that the pull exerted by the rods is on a line midway between the top and bottom of the stationary jaw, so as to reduce the strain upon the crusher-frame, and, furthermore, with this 60 arrangement the line of pull and the crushing-face of the stationary jaw can be substantially at right angles to each other. The length of the stroke of the movable jaw may be varied by changing the point of connection 65 between the tension-rods and the upper end of the pitman, and by so doing a uniformly effective crushing action may be secured regardless of the character of the rock.

Other features of improvement are herein- 70 after more fully set forth.

In the accompanying drawings, Figure 1 is a side elevation of a crushing-machine constructed in accordance with my invention. Fig. 2 is a section on line *xx* in Fig. 3. Fig. 75 3 is a plan of the machine shown in Fig. 1. Fig. 4 is a cross-section on line *yy* in Fig. 1. Fig. 5 is a similar section on line *ZZ* in Fig. 1. Fig. 6 is a detail view illustrating the manner of connecting the tension-rods with 80 the crusher-frame.

The crusher-frame *A* can be of any suitable design or construction and may be mounted or supported upon timbers substantially in the manner shown in Figs. 1 and 2. A stationary jaw *A'* is secured to or made integral with the said frame and in conjunction with a movable jaw *B* serves to provide a crushing-hopper for receiving the rock. The said movable jaw is preferably supported by a couple of swinging links or hangers *E* and is provided with a rearwardly-extending arm *b*. It will be observed that the said hangers are pivotally connected at their lower ends to the lower portion of the movable jaw, while their 95 upper ends are pivoted to the frame at points somewhat forward of their lower ends. The pitman *C*, which operates the movable jaw, is preferably actuated at its lower end by an eccentric, the shaft 1, upon which the cam is 100 mounted, being journaled in bearings 2 on the bottom of the frame and the pitman having

practically a pivotal or swinging connection with the movable jaw through the medium of the latter's arm *b*. It will be seen, however, that the point of connection between the arm 5 and pitman is at a point between the latter's top and bottom and that the upper end of the pitman is connected with the forward portion of the frame by a couple of parallel and longitudinally-extending tension-rods *D*. With 10 this arrangement the jaw *B* will have a combined vibratory and bodily forward-and-back movement and also a certain extent of bodily up-and-down movement. The tension-rods may have their rear ends connected to form a 15 sort of yoke—as, for instance, by constructing the yoke from a single rod bent into the desired form—and the upper end portion of the pitman can be provided with a plurality of bearing seats or grooves *c*, adapted to receive 20 and form a bearing for the cylindric portion *D'*, which connects the rear ends of the rods.

The crusher-frame is preferably cast with a couple of lugs or projections *a*. These lugs are provided with bores or openings through 25 which the forward end portions of the tension-rods are extended, and the projecting ends of the rods can be threaded and provided with nuts *d*. The openings or bores in the lugs may be tapered slightly, as shown in 30 Fig. 6, to permit the rods to have the requisite amount of vertical swing, and each lug can be provided with a removable bearing-block *a'*, having its face curved or otherwise adapted to provide a bearing upon which the 35 interposed washer *d'* may rock during the vibratory motion of the rods, and as a simple arrangement for preventing the blocks *a'* from turning they may each be provided with a reduced portion squared to fit a square 40 socket or countersink in the lug, substantially as illustrated in Fig. 6. With this arrangement the upper end of the vibratory pitman will swing about an axis located forward of the stationary jaw, and by referring 45 to Fig. 2 it will be seen that the pull exerted by the tension-rods upon the stationary jaw is on a line midway between the latter's top and bottom, or, in other words, that the tension-rods pull from the center of the station- 50 ary jaw in a way to permit the rods to sustain the greater part of the strain, and thereby reduce the strain upon the crusher-frame to a minimum. It will also be observed that the direction of pull exerted by the rods can 55 with such arrangement be substantially at right angles to the crushing-face of the stationary jaw and also to the links or hangers which support the movable jaw. The size of the product may be varied at will by sim- 60 ply rotating the nuts *d*, so as to adjust the movable jaw toward or away from the stationary jaw, it being seen that the vibratory rods *D*, each of which swings or vibrates about an axis forward of the movable jaw, is 65 adjustable longitudinally for the purpose of varying the length of rod between the pitman and the axis about which the rod vibrates.

The length of the stroke of the movable jaw may be varied according to the character of the rock by shifting the cross-piece *D'* of 70 the yoke from one to another of the notches *c* on the upper end of the pitman. In this way the machine is not only capable of readily producing any size of product, or, in other words, of crushing either fine or coarse, but 75 is also capable of a uniformly effective crushing action regardless of the character of the rock. The nuts *d* may be rotated while the machine is running, and in this way the attendant may change the product without stopping the machine.

By arranging the pitman to extend upwardly from the eccentric the adjustment of the connection between the vibratory tension-rods and the pitman in a direction toward the axis of the eccentric serves to lower the tension-rods. Such adjustment, therefore, shortens up the leverage between the axis of the eccentric and the point of connection between the tension-rods and the pitman, and in thus dropping the tension-rods toward a plane below the movable crushing-jaw longitudinal adjustment of the tension-rods will be necessary to maintain the relative position of the pitman, or if such longitudinal adjustment of the tension-rods is not made then the pitman will be caused to assume a different position relatively to the movable crushing-jaw. This variation in leverage and length of connecting-rods cannot, of course, be attained in the same way in a machine where the pitman extends downwardly, since in such case the downward adjustment of the tension-rods upon the pitman will lengthen the leverage and at the same time depress the tension-rods in a direction toward a plane below the movable jaw. The features of adjustment and arrangement herein involved are designed to coöperate with and affect the action of the movable crushing-jaw upon materials 95 of different size and hardness and to vary the degree of fineness of the product and the rapidity or retardation of its discharge from the hopper.

What I claim as my invention is—

A crushing-machine comprising a rotary driving-shaft provided with an eccentric; a pitman arranged upon and extending upwardly from the eccentric, and actuated thereby; a vibratory crushing-jaw arranged forward of the pitman and supported by swinging links pivotally connected at their lower ends with the lower portion of the movable crushing-jaw, and having their upper ends pivotally supported upon the body-frame of 125 the machine; a stationary crushing-jaw arranged opposite to and forward of the movable crushing-jaw and backed by the forward stationary part of the body-frame of the machine; a couple of vibratory tension-rods arranged as connections between the pitman and the stationary part of the body-frame and connected with the latter to swing about an axis forward of the movable jaw; means for 130

adjusting the length of each rod between said axis and the connection of the rod with the pitman; means for permitting the connection between the vibratory tension-rods and pitman to be adjusted toward and away from the axis of the driving-shaft; and a power-transmitting arm arranged between the movable jaw and the pitman and connecting with the latter at a point between the axis of the driving-shaft and the point of connection between the tension-rods and the pitman.
